UNITED STATES PATENT OFFICE.

SAMUEL G. CABELL, OF WASHINGTON, DISTRICT OF COLUMBIA, ASSIGNOR
TO CHARLES PELHAM AND FLORA B. CABELL, BOTH OF SAME PLACE.

SEAL-PADLOCK.

SPECIFICATION forming part of Letters Patent No. 292,407, dated January 22, 1884.

Application filed May 22, 1882. (No model.)

To all whom it may concern:

Be it known that I, SAMUEL G. CABELL, of Washington, in the District of Columbia, have invented certain Improvements in Seal-Padlocks, of which the following is a specification.

My invention consists in constructing the body or case of a lock with a hasp at its upper end, and with a flange or lip at the lower end, extending downward around and beyond the seal-holding devices to afford protection thereto, and to prevent the entrance of rain, dust, &c.; also, in the peculiar combination of devices for fastening the seal-holder; also, in the peculiar arrangement of dogs to hold the main bolt of the lock; also, in an alarm combined with the lock in the manner herein-after described.

In the accompanying drawings I have shown my lock in modified forms, all of which, however, embrace substantially the same features of invention.

Figure 1 is a side view of my lock provided with pivoted vibrating tumblers, a portion of the casing being broken away to expose the interior. Fig. 2 is a vertical section through the lock as constructed with a revolving barrel having sliding pins or tumblers, in place of the vibrating tumblers illustrated in the preceding figure. Fig. 3 is a vertical transverse section on the line $x-x$, Fig. 4 is a vertical transverse section on the line $y-y$, Fig. 2. Fig. 5 is a horizontal section on the line $z-z$, Fig. 2. Fig. 6 is a bottom plan view of the main locking-bolt. Figs. 7, 8, and 9 are vertical sections of different arrangements for locking the bolt. Fig. 10 is a view showing the manner in which the free end of the hasp closes upon and around the case of the lock. Fig. 11 is a cross-section of the rotary barrel employed in the plan shown in Fig. 1. Figs. 12 and 13 are sectional views illustrating the construction and arrangement of the alarm mechanism.

I construct my lock, as shown, of a flat rectangular form, with the hasp at its upper end, and with the key-hole and seal-retaining devices within a recess in the lower end. The case or body consists of an outside shell, A, to

which the bail or hasp is attached at the upper end, and of an inside body or block, B, to which all the working parts are attached. The shell A is cast complete in one piece, with its upper end closed, but with its entire lower end open, and with bands or enlargements e around its ends, for the purpose of giving additional strength and affording additional security to those parts most liable to injury. The hasp or bail C is pivoted between studs f, formed upon the upper end of the body, the latter being left complete, or without openings therein, in order to prevent the entrance of water, dust, and other foreign bodies. At its free end the hasp has the usual neck entering the opening in the body to engage with the locking-bolt E. As shown in the drawings, that portion of the body immediately around the hasp-opening is raised or elevated, and the end of the hasp made of suitable form to fit over and upon the same, as clearly indicated in Figs. 1, 2, and 10. This construction forms what I denominate a "water-shed," and serves to prevent water from finding its way into the working mechanism when the lock is suspended by the hasp in its ordinary pendent position. The construction of the lock-body and the two parts A and B is not claimed herein, as it will be made the subject of a separate application.

Referring to the various figures, it will be seen that the hasp is locked in its closed position by means of a horizontal sliding bolt, E, located in the upper end of the case, and thrown forward, when released, by means of a flat spring, H, acting against its rear end. In order to secure the locking of the bolt when the hasp is closed, I provide a vertical sliding bolt or dog, G, bearing at its lower end upon a spiral spring in such manner that when the bolt E is retracted by means of the key the dog G is thrown upward past its forward end, in the position represented in Fig. 2, thereby holding the bolt back. When the hasp is closed, its end or nose depresses the dog G, whereupon the bolt is thrown forward by the spring and caused to engage with the hasp. The dog G is made of such form that when elevated by the spring it closes tightly the

opening through which the end of the hasp enters, thus preventing the entrance of foreign matters into the lock.

As a means of securing the bolt in its locked 5 position, I make use of a series of vibrating tumblers, N—such as shown in Fig. 1—or sliding pin-tumblers in a rotating barrel, as shown in Fig. 2. Referring to the pivoted tumblers of Fig. 1, they may be made of any ordinary 10 construction. They may be pivoted to the case and arranged to engage with the bolt, or pivoted to the bolt and arranged to engage with a stud, o', formed on the interior of the lock-case, as shown in the drawings, the arrangement 15 of these tumblers constituting no part of the present invention. As shown in the various figures, the lower end of the lock-case is deeply recessed around the key-hole, in order to permit the insertion of the seal-holding devices K therein. These devices consist, in the present instance, of a hinged lid or cover arranged to close upon the seal and hold the latter in position over the key-hole. The seal-holder is provided with a central 20 opening through which to pass the key, this opening being closed, when required, by means of a hinged lid or door, W. It will be observed that the recess in the lower end of the case causes the latter to extend downward 25 on all sides around and beyond the seal-holding devices. This is an important feature, inasmuch as this depending edge serves, when the lock is suspended in its usual position, effectually to prevent the entrance of rain or 30 snow into the key-hole or seal-holding devices, thus avoiding the difficulty which is commonly experienced in this regard. In order to fasten the seal-holding devices K, I employ 35 a dog or locking device of any suitable construction, operating by means of the same 40 spring which elevates the dog G.

In Fig. 2 the locking device for the seal-holder consists of the pivoted spring-actuated dog M, having a hooked end to engage automatically over the seal-holder when the latter 45 is closed. When the hasp is closed, it serves to hold the sliding bolt G downward upon the rear end of the hook M in such manner as to keep the latter in engagement with the seal-holder. In Fig. 7 the seal-holder is secured 50 by a sliding spring-bolt, which is locked by means of an extended neck on the lower end of the sliding dog G. In Fig. 8 the seal-holder is pivoted at h' and secured by the end 55 of the dog G, bearing thereon upon the top and in rear of the pivot. In Fig. 9 the seal-holder is arranged to slide upon its pivot, so as to engage at one end in a recess in the side of the case, and is prevented from disengaging by 60 means of the dog G engaging in its end, as shown. A slight depression is made in the case of the lock above the seal-holder to receive the seal, and pins are provided, both upon the body and upon the revolving barrel, to 65 engage with the seal and insure the destruction of the same when the barrel is revolved.

Instead of making use of the vibratory tumblers represented in Fig. 1, I may employ, in connection with the barrel, the sliding or pin tumblers, similar to those employed in the 70 well-known "Yale" lock.

The retraction of the bolt after it has been unlocked is effected by means of a stud or pin, b, mounted eccentrically on the upper end of a rotating barrel or hub, F, mounted 75 vertically in the center of the lock and provided, as clearly shown in Fig. 11, with a longitudinal slit or opening, through which the key is inserted from the lower end of the lock, the key serving the twofold purpose of adjusting the tumblers and releasing the bail, and of imparting the rotary motion to the barrel F. It will of course be understood that, as in other locks of this class, the key-hole corresponding with the slit in the barrel 80 is made in the lower end of the body. Inasmuch as it is necessary, after the retraction of the bolt, that the barrel shall be turned to its original position in order to permit the removal of the key, and the bolt meanwhile left 85 in its backward or unlocked position, so that the hasp may be locked automatically when closed, it is necessary to provide means by which the bolt may be caused to re-engage with the stud b when the bolt is thrown forward to a locked position. The necessity for causing the bolt to re-engage with the stud b upon moving forward arises from the fact that this engagement is the only means of preventing the bolt from being jarred or driven 90 backward out of engagement with the hasp. I therefore provide the bolt, as shown in Figs. 2 and 6, with a pivoted hook or dog, n, acted upon by a spring, and arranged to engage automatically with the stud b on the barrel when 95 the bolt is moved to a locked position. In retracting the bolt the stud acts upon the dog, or upon a shoulder, n', formed on the bolt, as shown in Fig. 6.

For many of the purposes to which I propose to apply my lock it is highly important that provision shall be made for preventing it from being secretly opened by those who may be in possession of a suitable key. I therefore attach an alarm mechanism, such as shown 110 in Figs. 12 and 13. This alarm consists of a bell, A', a vibrating striker or hammer, B', a pallet or escapement, C', to which the striker is attached, a rotating toothed wheel, D', by which the pallet is operated, and a coiled 115 spring, E', by which the wheel is driven. The wheel is mounted loosely on a winding-arbor, F', and the spring is connected at one end with the arbor, and at the opposite end with the wheel, as shown. Near the outer end the 120 winding-arbor is provided with a ratchet-wheel, G', which is engaged and held by means of a pawl, H'. An arm, I', attached to the main lock-bolt, extends through the main body of the lock in such position that when the bolt 125 is in its locked position the arm engages against the pallet and prevents its motion. A supple-

mental case or shell, J', applied to the side of lock-body, covers and conceals the entire alarm mechanism, with the exception of the winding-arbor, which protrudes as shown.

5 The action is as follows: When the lock-bolt is thrown forward, the arm I' rests against and holds the alarm, as shown in Fig. 13. The spring is then wound by means of a key or equivalent device applied to the end of the 10 protruding arbor. The parts remain quietly in this position until the lock-bolt is moved backward, whereupon its arm I' releases the pallet and the alarm is at once sounded, giving audible notice to a considerable distance from 15 the lock.

I am aware that padlocks have been recessed and provided with a key-hole in the lower end, and this I do not claim. In the lock represented in the drawings, however, a peculiar 20 relationship exists between the seal-holding devices and the recessed case, in that the case, extending down beyond the seal-holding devices on all sides, serves the twofold purpose of protecting said devices against attempts to tamper therewith, and also against the admission of rain and snow, which would have the effect of destroying the paper or other soluble seal commonly employed.

The present invention is restricted to those 25 matters and things which are hereinafter claimed, and as to all matters which may be described or shown, but which are not claimed, the right is reserved to make the same the subject of a separate application.

30 Having thus described my invention, what I claim is—

1. In a padlock, the combination of a recessed case or body and a seal-holding device, the case or body extending below and embracing said device, as and for the purpose 40 described.

2. In combination with the hasp and the sliding bolt E, provided with the hook or dog n, the hub or barrel F, provided with locking pins or tumblers, and a stud, b, adapted to co-operate with the hook n, as shown and described, whereby the bolt is permitted to remain in its unlocked position until the hasp has been closed, but locked rigidly after being moved forward. 45

3. In a padlock, the combination of the swinging hasp, the main locking-bolt E, a seal-holder, means for holding said seal-holder in a closed position, and a sliding bolt, G, adapted to serve the twofold purpose of preventing 50 the unlocking of the seal-holder and of holding the main bolt in an unlocked position, said bolt G arranged to be operated by the hasp of the lock.

4. In a padlock having the locking mechanism in one compartment and an alarm mechanism in another compartment of the lock-case, the combination of the hasp-locking bolt provided with an alarm-operating arm extending through the separating-diaphragm, with the alarm mechanism, substantially as specified. 60 65
